United States Patent Office

Des. 228,896

Patented Oct. 30, 1973

228,896

PALLET

Dennis M. Melnick and Mark Kubick, Baden, Pa., assignors to Pallet Development Inc., Ambridge, Pa.

Filed Sept. 29, 1971, Ser. No. 184,990

Term of patent 14 years

Int. Cl. D12—99

U.S. Cl. D14—3 N

Fig. 1

Fig. 2

FIG. 1 is an isometric view particularly showing the top construction of a pallet employing our new design; and

FIG. 2 is an isometric view on the same scale as FIG. 1 particularly showing the bottom construction of a pallet employing our new design it being understood that in this view the pallet has been turned over and rotated 180° to show that the opposite end and the opposite side exactly correspond to the end and side that are illustrated in FIG. 1.

We claim:

The ornamental design for a pallet, as shown and described.
